SLUG CASTING MACHINE

Anthony J. Stouges, Queens Village, N. Y., assignor to Mergenthaler Linotype Company, New York, N. Y., a corporation of New York

Application June 19, 1931, Serial No. 545,398

89 Claims. (Cl. 199—47)

This invention is directed to an improved automatic slug casting machine capable of producing type bars or slugs with characters ranging in size from 5½ pt. to 144 pt., a variation which 5 will take care of all the practical requirements of the trade.

The machine is adapted to handle not only the regular linotype matrices (in order that the vast 10 number of outstanding matrix fonts may be utilized if desired) but in addition matrices of special form which could not be handled in the regular commercial machines and which are herein intended for hand composition only. The special matrices employed include those of 15 one size for characters ranging up to 72 pt. in height, and those of a larger size for characters ranging from 72 pt. to 144 pt.

In the use of the machine, the matrices are composed in line in a hand stick or holder which 20 then is placed in the machine and the composed line thereafter presented automatically to the casting mechanism, which includes four molds, two of regular form to cooperate with the regular matrices, and two of special form to cooperate 25 with the special matrices of both sizes. During each cycle of operation, a slug is cast in the selected mold, ejected therefrom, trimmed and finally stacked in a galley arranged conveniently at the front of the machine.

30 The several molds, each of which comprises as usual fixed body portions and adjustable cap portions, are all carried in a rotatable wheel or disc and have their inner casting surfaces (those nearer to the axis of the disc) located at the 35 same distance therefrom, so that said casting surfaces will all stand in the same horizontal and vertical planes when the selected mold occupies the slug casting and ejecting positions, respectively. This particular arrangement is common 40 to the commercial linotype machines and is very advantageous for reasons well understood in the art.

The characters of the regular matrix fonts are 45 positioned as usual with reference to a datum line which passes through the tops of the upper case characters (inverted), all characters throughout the various fonts growing upwardly from this line as their size increases. In casting from such matrices, therefore, the composed lines 50 irrespective of character size are supported at a common level in the casting position and the width of the mold slot is varied to suit the particular font in use merely by adjusting the cap portion of the mold toward or from the body portion. The main disadvantage of these regu-

lar matrix fonts however is that it is impossible to mix different sizes of characters in the same line due to the top alinement.

The characters of the special matrix fonts herein employed, on the other hand, are positioned with reference to a common datum line which passes through the bases of the upper case characters (inverted), so that matrices of different sizes may be composed in the same line and still be properly alined. Although the characters as thus designed for base alinement grow downwardly from the common datum line as their size increases, the present invention enables slugs of any selected body size to be produced from these special matrices in the customary 60 way, i. e. through an adjustment only of the cap portions of the corresponding molds, this being accomplished by presenting the matrix lines to the molds at one or another of a series of different levels according to the size of the font in use. 65 The customary matrix ears and mold alining ribs are dispensed with and the required horizontal alinement of the matrix characters with the mold slot (ordinarily effected by the direct engagement of the matrix ears with the mold ribs) is brought 70 about by definitely locating both the matrix line and the mold in a truly horizontal position on a common supporting frame during the slug casting operation. Ordinarily, for faces above 75 14 pt., the special molds employed should preferably be of the ordinary "recessed type" so that the cast slugs will be comparatively light in weight and the top portions of the slugs properly supported as usual by a series of vertical 80 reinforcing ribs.

85 In carrying out the invention, it is also proposed to make the special molds lower or of less depth than the regular molds and to form the special matrices with routing notches sufficiently deep to compensate for the reduced 90 height of the molds. By so doing, as will later appear, it is possible to cast in a plain mold of 95 one body size, say 12 pt. or 14 pt., L-shaped or overhanging slugs with characters varying in height, say from 42 pt. to 72 pt. In the case of 100 the larger special matrices, having the 72 pt. to 144 pt. range previously mentioned, it is proposed to use them primarily in conjunction with a special mold of the "recessed" type so as to produce an L-shaped or overhanging slug with 105 a ribbed body portion (rather than with a solid body portion). The width of the overhanging top portions as well as the thickness of the body portions of these particular slugs may be 110 varied to suit different arrangements of the type

matter in the printing forms. For example, in casting a 120 pt. type face, the slug may have a 72 pt. body and a 48 pt. overhang, or a 48 pt. body with a 72 pt. overhang, these dimensions being purely illustrative. "Furniture" material required in making up the printing forms may also be cast in the low special molds either from a line of blank matrices without routing notches or from quad blocks of ordinary construction.

10 Various other features are included in the improved machine and will be fully set forth in the detailed description to follow.

In the accompanying drawings, the various improvements have been shown merely in preferred form and by way of example and obviously many changes and variations may be made therein and in their mode of adaptation and still be comprised within the scope of the invention. It should, therefore, be understood that the invention is not limited to any specific form or embodiment, except in so far as such limitations are specified in the claims.

140 Fig. 35 is a detail perspective view of a portion of a ribbed slug formed with a top portion overhanging the ribbed side of the slug and cast in 60 pt. mold from the special 72 pt. matrices.

General organization and operation of machine 135

The disc A is rotatably mounted as usual on the fore-and-aft mold slide A¹ and is equipped, in the present instance, with four slotted molds, any selected one of which may be brought into use by the rotary adjustment of the disc as effected in the usual way by means of the driving pinion A². As the machine is started by the engagement of the main driving clutch (not shown), the cam shaft R (Fig. 2) is rotated slowly, and the mold disc or carrier A is given a quarter turn in an anti-clockwise direction (looking from the front of the machine) to locate the selected mold in the casting position. The elevator or transporter B then descends to position a line of 145

matrices (previously delivered thereto) in front of the active mold, where the line is justified between the clamping jaws C^1 , C^2 mounted in the fixed vertically disposed vise frame D. The mold slide A^1 is now moved forward to bring the active mold up against the matrix line, which thereby closes the mold slot at the front, and the metal pot E is likewise advanced from its normal position behind the disc A to bring the mouthpiece E^1 thereof up against the back of the mold, thereby closing the mold slot at the rear. The descent of the pot plungers immediately follows, and molten metal is ejected from the pot into the mold to produce the cast slug. The pot plungers are depressed by means of a heavy pull spring E^2 , the force of which is imparted to the plungers through the rock shaft or pivot rod E^3 and the intermediate lever E^4 mounted on said rod. As the cycle of operation proceeds and the cam shaft R continues to revolve, the pot plungers are raised, the metal pot E and the mold slide A^1 are caused to recede, and the disc A is given a three-quarter turn in the same direction as before to carry the mold with the contained slug to a vertical position between the ejector blade F at the rear and the trimming knives G^1 , G^2 at the front. The mold slide A^1 is next advanced a second time to locate the mold against the vise frame D in close relation to the knives G^1 , G^2 , whereupon the ejector blade F is thrust forwardly to eject the slug from the mold. By the forward movement of the ejector blade F, the slug is forced between the two knives, whose cutting edges trim the side faces of the slug, and the latter is subsequently delivered to and stacked in the galley S supported from the vise frame D by the brackets S^1 . About this time and as the cycle of operation is completed, the line transporter B and the mold disc A are restored to their original and normal positions of rest.

The vise frame D, which includes the elongated horizontal cap member D^1 , is hinged at its lower end on the pivot rod D^2 mounted in the base frame T and is held securely at the top against suitable banking surfaces t^1 , t^2 by the pair of clamping bolts D^3 mounted in the cap D^1 near the opposite ends thereof. The banking surface t^1 is formed at the upper end of the main bracket T^1 rising from the base frame T at one side of the machine, and the other banking surface t^2 is formed on a lug or projection jutting forwardly from the column T^2 rising from the base frame at the opposite side of the machine.

The vise frame D is further equipped with an automatic device for stopping the operation of the machine when, for any reason, the transporter B in its descent fails to reach a predetermined casting level. This device (see Figs. 2, 3 and 4) comprises the vertically disposed control rod J, which is held resiliently in a normal position, with its upper end protruding above the vise cap D^1 , by the spring J^1 anchored to the frame D and tending to pull the rod upwardly. The rod J, as may be observed (Fig. 3), is sufficiently loose in its top bearing to permit its lower end to be swung forwardly, but under normal conditions it is maintained in its vertical position by one arm of the horizontal lever J^2 also mounted in the vise frame D. The other arm of this lever J^3 (Fig. 1) is located in operative relation to the fore-and-aft machine control rod K which is adapted when pushed rearwardly to effect the disengagement of the main driving clutch against the tension of its spring (not shown).

The forward movement of the rod J is effected by means of the spring plunger J^3 mounted in the vise frame D and operable from the rear, when the mold disc A is advanced for the casting and ejecting operations, by one or another of the four studs a (Fig. 24) associated with the respective molds and projecting from the front face of the mold disk. The front end of the plunger J^3 is disposed in operative relation to the lip j secured to the rod J and which is moved into and out of the path of the plunger as the rod is raised and lowered. If the rod J is depressed as the transporter B comes to rest at the proper casting level and is again depressed prior to the ejecting period, it will be unaffected by the plunger J^3 and the cycle of operation will proceed uninterruptedly, but otherwise the lower end of the rod will be swung forwardly by the plunger and bring about the stoppage of the machine through the medium of the horizontal lever J^2 and the clutch control rod K.

So far as described, the construction and mode of operation of the various parts, except as hereinafter pointed out, are or may be the same as those embodied in the commercial linotype machines.

Line transfer devices

The matrix lines (which are composed by hand and are of a given length, preferably 42 ems) are delivered (see Fig. 1) by means of a manually operated carriage 1 to the transporter B from a table 2 mounted on the column T^2 and wherewith the transporter is adapted to register when the machine is at rest. The carriage 1 is slidably mounted in fixed horizontal guideways 3, supported on the table 2, and is operable by a handle 4 rising from one end of the carriage. The carriage also includes a pair of depending fingers 5 between which the composed lines are positioned on the table 2 and whereby a line may be shifted into and out of the transporter B as the carriage is reciprocated. In operating the parts, the carriage 1 is moved to the dotted position indicated in Fig. 1, in order to deliver a composed line of matrices from the table into the transporter B. The machine is then started manually, and after the cycle of operation has been completed, the carriage is returned to its original position to transfer the line from the transporter back onto the table 2, the line during the cycle of operation being lowered from its position between the fingers 5 when the transporter descends preparatory to the slug casting operation, and later being repositioned between the fingers when the transporter rises after the slug casting operation.

The transfer devices above described form the subject matter of Patent No. 1,899,648, and hence no claims will be made herein on such subject matter.

The means for inaugurating each machine cycle (see Fig. 1) consists of a vertically disposed rock shaft 6 mounted in the main frame and provided near its upper end with an operating handle 7 arranged at a convenient level adjacent the table 2. At its lower end, the rock shaft is provided with a lateral crank arm 8 connected by means of linkage 9 to a fore-and-aft rod K^1 located directly beneath the corresponding rod K previously referred to and which also controls the operation of the main driving clutch. Both rods K, K^1 are common to the commercial linotype machines and their mode of operation is so well known to those skilled in the art that any further explanation is unnecessary.

Matrices

The regular linotype matrices Y and Y^1 , see Figs. 20 and 33, are formed as usual with the upper projecting ears y^1 and the lower projecting ears y^2 . The matrices Y are provided with two superposed characters y^3 , being confined to the smaller text fonts ranging up to 14 pt., whereas the matrices Y^1 are provided with but a single character y^4 , being confined to the large head-letter 10 and display fonts ranging above 14 pt.

The special matrices X , as may be noted (Fig. 32), are of plain rectangular form, being devoid of projecting ears, and are considerably longer than the regular matrices Y , Y^1 , in order to 15 increase (to a still greater degree than would be afforded by the mere elimination of the projecting ears) the space allotted to the characters. The characters x of the matrices X , as shown herein, have a range up to 72 pt. and are positioned on the casting edges of the matrices, throughout the several fonts, with reference to a common datum line located at a given distance from the bottom edges of the matrices. In the present embodiment, (see Fig. 10), this 20 datum line $a-a$ passes through the bases of the characters, and the bottom edges of the matrices are dressed to provide suitable alining surfaces x^1 , so that when the matrices are composed side by side in line and supported by their bottom edges, the characters will be properly alined at their bases irrespective of size or font. For reasons later to be pointed out, the matrices X are formed in their casting edges with transverse routing notches or recesses x^2 of slightly 25 greater than the normal depth, and the characters x are punched in the bottoms of these recesses.

Blank matrices X^1 (Fig. 34), similar in form to the matrices X but devoid of the recesses x^2 , 40 are used as spacers between words or in any other place in line where spacing is required.

The character matrices X and blank matrices X^1 are also formed at their upper ends with short extensions x^3 , which are of reduced width 45 so as to provide open notches x^4 in the front edges of the matrices and corresponding notches x^5 in the rear edges thereof.

The matrix equipment includes other special matrices Z , capable of bearing characters ranging from 72 pt. to 144 pt. These particular matrices Z may not only be used alone but are also adapted for use in conjunction with the matrices X (see Figs. 26 and 28), the characters z thereof being positioned throughout the several 50 fonts with reference to the same datum line $a-a$ passing through the bases of the characters. Except as to length, the matrices Z are similar to the matrices X , being formed in their casting edges with deep routing notches or recesses z^1 and at their upper ends with corresponding extensions z^2 . The alining surfaces of the matrices Z , however, are formed, not at their bottom edges (like the matrices X), but on the upper 55 walls z^4 of notches z^3 cut in their front edges and located at the same given distance from the datum line $a-a$. That is to say, when the matrices X and Z are properly composed in line, the walls z^4 of the matrices Z are adapted to register with the bottom edges x^1 of the matrices X , so 60 that all the characters of both kinds of matrices will aline at their bases irrespective of size.

Thin dummy or blank matrices Z^1 , which are identical in form and size with the character matrices Z , although formed without the routing 65 notches z^1 , are used in conjunction with the mat-

rices Z to prevent the escape of metal from the routing notches z^1 during the casting operation (see Figs. 26 and 28).

Molds and slugs

80

As before stated, the disc A (as shown in Fig. 24) is equipped with four molds L^1 , L^2 , L^3 and L^4 . The molds L^1 and L^2 are of regular construction and of normal height or depth to 85 cooperate with the regular matrices Y , Y^1 , in producing the common type of ribbed and plain slugs, respectively, (not shown); whereas, the molds L^3 and L^4 are of special construction and of slightly less than normal height or depth to 90 cooperate with the special and more deeply recessed matrices X or Z in producing, respectively, L-shaped slugs Q having an overhanging top portion Q^1 (as in Fig. 31), and slugs Q^2 having top portions Q^3 supported by reinforcing ribs Q^4 95 (as in Fig. 30). The mold L^4 may also be employed to produce ribbed slugs of the overhang type, as illustrated for example in Figs. 29 and 35, which will later be referred to.

Each of the several molds comprises a body 100 portion L^5 , a cap portion L^6 , and a pair of intermediate liners L^7 . The body portions L^5 provide the inner casting surfaces or the lower side walls l of the mold slots (those closer to the axis of the disc), the cap portions L^6 provide the outer 105 casting surfaces or the upper side walls l^1 of the mold slots (those farther removed from the axis of the disc), and the liners provide the end walls l^2 of the mold slots.

The body portions L^5 of the molds are screwed 110 fast to the disc A , and the inner casting surfaces l thereof are all (see Fig. 24) equidistant from the axis A^3 of the disc, so that each will occupy the same horizontal plane as well as the same vertical plane when the molds are brought into 115 the casting and ejecting positions, respectively. These casting surfaces l are coincident with the datum or constant line of the molds. The cap portions L^6 of the molds are adjustable in the usual way by the liners L^7 , which may be removed 120 and replaced by others of different thicknesses, whereby the width of the mold slots may be varied as desired.

The regular mold L^1 is representative of the so-called "recessed" or "head-letter" variety, having a range ordinarily from 14 pt. to 36 pt., and its cap portion is formed with core sections l^3 spaced apart and projecting into the mold cavity. The other regular mold L^2 is representative of the unrecessed variety, having a range below 14 125 pt. and being formed with plain flat inner and outer casting surfaces as shown. Both of these regular molds present front superposed alining ribs l^4 and intermediate grooves l^5 , as usual, to accommodate the lower projecting ears y^2 of the 130 matrices Y whether supported in the transporter B at the lower or the upper level during casting.

The special molds L^3 and L^4 are devoid of alining ribs or grooves in their front faces, which instead are made plain and flat throughout to 140 cooperate with the special earless matrices X and Z . Otherwise, however, the special molds are similar in construction to the regular molds L^1 and L^2 . Thus, the cap of the mold L^4 , like the cap of the mold L^1 , is formed with core sections l^6 , 145 and the cap of the mold L^3 , like the cap of the mold L^2 , is plain or unrecessed. The core sections l^6 , of course, are larger than the core sections l^3 , and the width of the mold slot is likewise proportionately greater.

150

The three molds L^1 , L^2 and L^4 , with their individual adjustments, provide for the production of slugs with body sizes ranging from $5\frac{1}{2}$ pt. to 72 pt., the fourth mold L^3 being used only for L -shaped slugs whose overhanging top portions are cast in the deeper recesses x^2 or z^1 of the special matrices X or Z before described. It will, of course, be understood that such an assortment of molds is merely illustrative and may be changed as required.

Two forms of safety members L^8 , L^9 , associated respectively with the regular and special molds, are provided to arrest the transporter B at abnormal levels and thus cause a stoppage of the machine under abnormal conditions. The precise manner in which they function will be explained later. These members (see Figs. 24 and 25) are fastened at common or corresponding points by screws and dowel pins l^1 to the disc A , but they vary in length in both directions from these points. At their bottom or inner ends, they are provided with distinguishing lips l^8 and at their tops or outer ends with banking surfaces l^9 . The lips l^8 engage in corresponding notches l^{10} formed in the contiguous ends of the mold bodies L^5 and located different distances from the inner casting surfaces l thereof according to the size or type of the mold. The members L^8 and L^9 are marked in "pts." to indicate the sizes of the molds with which they are associated, and they differ in form, as shown in Fig. 25, the members L^8 for the regular molds being substantially of the same width throughout, and the members L^9 for the special molds being recessed or cut away in one of their side faces as at l^{11} .

Alinement of matrices with molds

In the use of the regular two-letter matrices Y , the composed lines, irrespective of font, are presented to the plain or unrecessed mold L^2 , as in the commercial linotype machines, at either the normal upper level or the normal lower level to bring one or the other of their superposed characters into proper casting relation to the mold slot; and in the use of the larger or head-letter matrices Y^1 , the composed lines, irrespective of font, are presented to the recessed mold L^1 at the normal upper level to bring the single characters of those matrices likewise into proper casting relation to the mold slot.

On the other hand, in the use of the special matrices X , and due to the base alinement of their characters (instead of the usual top alinement as in the case of the regular matrices Y , Y^1), they are presented to the special mold L^3 or to the special mold L^4 at one of a number of different levels according to size or font in order that the characters may register properly with the mold slot. For example, when the plain mold L^3 is selected to produce L -shaped slugs Q (as in Fig. 31), the matrix lines of the different fonts will be supported at a series of low levels determined by the lengths of the descenders of the lower case characters (see Fig. 9); whereas, when the recessed mold L^4 is selected to produce ribbed slugs Q^2 with no overhang (as in Fig. 30), the matrix lines of the different fonts will be supported at a series of higher levels determined by the heights of the upper case characters (see Fig. 8).

In the former case, the upper ends of the recesses or routing notches x^2 (see Fig. 13) register with the outer casting surface l^1 of the mold L^3 , while the lower ends terminate below the inner casting surface l at a point determined by the size or height of the characters of the particular font

in use, it being noted that such overlapping relation of the matrices is permitted by the plain flat extended front face of the mold body portion L^5 . In the latter case, the upper and lower ends of the routing notches x^2 (see Fig. 12) register with the outer and inner casting surfaces l , l^1 , respectively, of the mold L^4 , there being no overlapping relation in this instance.

The mold L^3 , therefore, requires no adjustment in producing the L -shaped slugs of various face sizes (although it may be adjusted to vary the body size of the slugs), while the mold L^4 must be adjusted for the various face or body sizes by changing the liners L^7 as commonly practiced, unless an entirely new mold with the proper cap adjustment is substituted for the mold L^4 , as of course could be done.

As will be understood, the slugs Q^2 cast in the mold L^4 are self-supporting, whereas the L -shaped slugs Q cast in the mold L^3 require the use of filler pieces or blank slugs to give support to their overhanging top portions when assembled in the printing forms.

By comparing Figs. 8 and 9, it will be seen that the difference in the length of the descenders of the lower case characters as between fonts is considerably less than the difference in height of the upper case characters as between fonts. Consequently, the upper series of levels at which the matrices are presented to the mold L^4 , and the lower series of levels at which the matrices are presented to the mold L^3 are caused to vary accordingly.

For faces ranging from 72 pt. to 144 pt., it is proposed to employ special matrices Z solely in connection with the special mold L^4 as illustrated in Fig. 27, so as to cast slugs Q^5 (as in Fig. 29) having a top portion Q^6 supported at one side of the slug body by reinforcing ribs Q^7 and extending beyond or overhanging the other side of the slug body. In such instance, the matrix lines irrespective of font are presented to the mold L^4 at the 72 pt. level, since that part of the face located on the body of the slug will always correspond to a 72 pt. font, the remaining part of the face overhanging the slug body as in the case of the slug Q . Although a 72 pt. mold may be used in casting all slugs from the various fonts of these particular matrices Z , similar molds of selected body sizes below 72 pt. could also be used, if desired, in order that the relative widths of the slug body and overhang portion may be varied to suit different forms of type matter. In using a smaller size mold, however, the matrix lines will be presented to the mold at a corresponding lower level.

Furthermore, ribbed slugs (not shown) having a top portion or printing face extending beyond or overhanging both sides of the slug body could also be cast from the matrices Z in a mold L^4 , say, for example, by presenting a 144 pt. matrix line at the 72 pt. level to a 60 pt. mold, the overhang in such instance being 12 pt. on the ribbed side and 72 pt. on the other.

It is also contemplated to cast slugs of a still different kind, as in Fig. 35, which shows a ribbed slug Q^8 formed with a top or character bearing portion Q^9 , projecting beyond or overhanging the reinforcing ribs Q^{10} . In producing such slugs, a line of matrices X of a given font, say 60 pt., is presented at the corresponding level to a mold L^4 of smaller body size, say 48 pt. In such cases, of course, the matrix characters will extend above the outer casting surface l^1 of the mold as permitted by the flat extended surface of the mold

lip l^4 . With slugs of this kind, the top portion may be cut to size between ribs and reinforced or supported by filler pieces or blank slugs throughout its length, including the end where it is cut,— 5 an advantage which would apply to ribbed slugs of all sizes and particularly to slugs of the larger sizes.

Line transporter or elevator

10 The line transporter or elevator B which carries the composed matrix lines to and from the casting position, (see Figs. 1, 2, 6, and 7) comprises an elongated vertically disposed body portion B¹ slidably mounted in the fixed vise frame D, a top flange B² which overhangs said frame, and a horizontally disposed head portion B³, which depends from the rear edge of the flange B². The head portion B³, wherein the matrix lines are sustained, consists of front and rear side walls B⁴ and B⁵ and an intermediate spacing block B⁶ arranged at one end of the head.

15 The front wall B⁴ (which, as shown, is much wider and thicker than the opposing rear wall B⁵) is provided near the bottom with a horizontal supporting ledge b, and is formed near the center with an opposed shoulder b¹. The lower edge b¹⁶ of the rear side wall B⁵ constitutes a second shoulder in horizontal alinement with the shoulder b¹, and as may be observed (Figs. 6 and 7), the two shoulders being located at a common distance above the ledge b, are adapted to fit or snugly engage in the front and rear notches x⁴, x⁵ formed in the upper ends of the matrices X and X¹ when the latter are supported on the ledge b. In entering the transporter, therefore, said matrices will not only be sustained by means of their upper extensions x³ in an upright position on the ledge b, but will be maintained by the shoulders b¹ and b¹⁶, with their bottom alining surfaces x¹ seated upon said ledge so as to insure the required vertical alinement of the matrix characters with one another. The rear face of the wall B⁵ is flush with the rear casting edges of the matrices and consequently will fit tightly up against the flat front face of the mold or the lip portion l⁴ thereof.

20 In the case of the matrices Z and Z¹, the composed lines, whether they be mixed with the matrices X and X¹ or not, will be inserted endwise into the transporter B by hand. The notches z³ in the front edges of the matrices are so located as to engage the supporting ledge b of the transporter, and the extensions z² at the upper ends of the matrices are adapted to be confined, like those of the matrices X and X¹, between the front and rear side walls B⁴, B⁵, so that the characters z of the matrices Z when supported in the transporter will be vertically alined with one another or with the characters x of the matrices X for presentation to the mold.

25 In adapting the machine to handle the regular linotype matrices Y and Y¹, the transporter B is equipped (as shown in Figs. 14 and 15) with a removable auxiliary back plate B⁷, the latter being detachably connected by means of a tongue and groove B⁸ to the rear wall B⁵ of the transporter head B³ and provided at its lower edge with a horizontal sustaining ledge b². The plate B⁷ (see Fig. 14) is considerably wider than the rear wall B⁵ of the transporter, so that the ledge b² thereof will be positioned, when the plate is attached, directly beneath the upper rear projecting ears y¹ of the matrices Y and Y¹ when supported on the ledge b. At one end, the plate B⁷ is provided with a finger-hole b³ to facilitate its removal from the transporter, and adjacent

30 said hole the plate is provided with a recess b⁴ to cooperate with a detent b⁵ (Fig. 16), which is mounted in the head B³ and maintains the plate against endwise displacement from its proper position.

The transporter is further provided with a fixed horizontal bar or strip B⁹ mounted on the front wall B⁴ between the ledge b and shoulder b¹ and whose upper edge is in horizontal alinement with the ledge b² and is adapted to underlie the upper front projecting ears y¹ of the matrices. The bar B⁹ is formed at the bottom with a longitudinal matrix supporting ledge b⁶ and fits up against the front edges of the matrices Y and Y¹ to give them the required edgewise support during the casting operation. The two-letter matrices Y are supported at the lower level on the ledge b when their upper characters are selected for use, and they are supported at the higher or so-called "auxiliary level" upon the ledge b⁶ when their lower characters are selected for use. The single or "head-letter" matrices Y¹, having but one character, are always supported on the lower ledge b, and the same is true of the special matrices for the same reason.

35 In order to locate the composed matrix lines in a truly horizontal position during casting, the transporter B, as best shown in Fig. 4, is provided in the overhead flange B² with two banking screws B¹⁰ (instead of the single one usually employed), and these screws are arranged at the opposite edges of the overhead flange B² so as to sustain the head B³ of the transporter squarely, and without danger of tilting, upon the vise cap D¹ when the transporter descends to 40 casting position. A third screw B¹¹ is arranged between the two screws B¹⁰ at a point vertically alined with the vise automatic control rod J to actuate it in the regular way.

45 The operation of the transporter is automatic, 45 being effected by means of a large angular lever B¹² (Figs. 1 and 2) from a rotary edge cam R¹ mounted on the cam shaft R. The lever B¹² is pivoted on a fixed axis B³⁰ in the base frame T below the cam shaft and is operated by an intermediate upright lever B¹³ pivoted on the same axis and provided with a roller b⁷ which tracks upon the cam R¹. The shorter arm of the lever B¹² is connected by an adjusting screw b⁸ to the lever B¹³, and the longer arm thereof extends 50 forwardly to the front of the machine, where it is connected by a link b⁹ to the transporter B through a vertical rod B¹⁴.

55 The rod B¹⁴ is slidably mounted near its opposite ends in alined bearings b¹⁰ projecting from the body portion B¹ of the transporter, and is provided between said bearings with a compression spring b¹¹, which latter bears upwardly against a collar b¹² on the rod and reacts against the lower bearing b¹⁰. The rod B¹⁴ is also provided with 60 a pair of adjusting nuts b¹³ arranged below the lower bearing b¹⁰, against which they are normally held by the spring b¹¹ and by which the upward movement of the rod is limited.

65 According to this arrangement, the transporter 65 B is allowed to descend by its own weight to the casting position under the control of the cam R¹, but is positively lifted therefrom by said cam to its receiving position, the nuts b¹³ during both operations maintaining their engagement with 70 the lower bearing b¹⁰.

The cam R¹, however, as will be noted (see Fig. 2), is provided with an auxiliary segmental track member R², which is adapted, as the transporter is arrested in its descent by the vise frame 75

D, to engage the roller 5⁷ of the lever B¹³ and rock the latter forwardly. This rocking motion is imparted to the lever B¹², and the longer arm thereof through the link b⁹ pulls the rod B¹⁴ downwardly and compresses the spring b¹¹ against the lower bearing b¹⁰, thus seating the transporter under pressure firmly and squarely in its casting position as determined by its two banking screws B¹⁰.

The upward movement of the transporter is limited by a set screw b¹⁴ mounted in the base frame T and which, in the present instance, is arranged to engage a lug b¹⁵ protruding from the lever B¹². By this arrangement, the opening and closing of the vise frame may be effected in any position of the transporter B.

Transporter level determining means

The means herein provided for locating the special matrices as well as the regular matrices of the various fonts in proper casting relation to the corresponding molds, include a pair of duplicate stepped banking blocks D⁴, D⁵, arranged to cooperate with the banking screws B¹⁰ of the transporter B. Each of said blocks (Fig. 4) is provided with an upper series of steps d and a lower series of steps d¹, the individual steps of both series being spaced predetermined distances above the top surface of the vise frame D to serve different matrix fonts and molds.

The blocks D⁴ and D⁵ are carried by a long thin plate D⁶ slidably mounted, by means of retaining gibs or guideways D⁷, upon the vise cap D¹ and capable of adjustment to bring any selected pair of steps d or d¹ beneath the banking screws B¹⁰. Consequently, as the transporter B descends to the casting position, the matrix line supported in the head B³ may be arrested at different levels by the steps d or d¹ according to the adjusted position of the slide plate D⁶.

The steps d of the upper series determine the levels at which the special matrices are presented to the special mold L⁴, and the steps d¹ of the lower series determine the levels at which the special matrices are presented to the special mold L³. Thus, when the slide plate D⁶ is adjusted toward the right (Fig. 4) to bring the uppermost pair of steps d into vertical alinement with the banking screws B¹⁰, the transporter will be arrested at the highest level in the position shown in Figs. 7 and 12 so as, for example, to locate the 72 pt. matrices X in casting relation to a 72 pt. recessed mold L⁴; whereas, when said plate is adjusted in the opposite direction to bring the lowermost pair of steps d¹ into vertical alinement with the screws B¹⁰, the transporter will be arrested at the lowermost level shown in Figs. 6 and 13 so as, for example, to locate the 72 pt. matrices X in casting relation to a 14 pt. plain mold L³. The intermediate pairs of steps of series d or d¹ serve in similar fashion, by the proper adjustment of the plate D⁶, to support the transporter at as many different levels for the various other matrix fonts. In Fig. 4, the various steps are marked with the sizes of the matrix fonts which they represent.

In order that the matrices Z may be used in the same line with the matrices X, the bases of their characters z are located with reference to the same datum line a—a, as before stated, but due to the limited space between said datum line and the upper ends of the routing notches z¹, it is proposed to limit these particular fonts to upper case characters or caps only. Hence, the steps d of the upper series selected to locate the composed

lines at the proper casting level should correspond to the size of the matrices X with which the matrices Z are combined, or if the line is composed entirely of the large matrices Z, the steps d selected should correspond to the body size of the mold, unless it is desired to produce slugs (as before mentioned) having a top portion which overhangs the reinforcing ribs as in Fig. 35, in which case the procedure before outlined may be followed.

In casting from the regular two-letter matrices Y in mold L², the uppermost pair of steps d (used for the 72 pt. special matrices) is adapted to serve in locating the transporter at the normal upper auxiliary level, and an extra pair of lower steps d² associated with the upper series of steps d is provided to locate the transporter at the normal lower level. In this connection, it will be understood that the head-letter matrices Y¹ (Fig. 33), having but one character, will be supported by the uppermost pair of steps d at the auxiliary level only. It will also be understood that whenever the transporter is arrested at the upper auxiliary level, the matrices Y and Y¹ should be supported in the transporter on the lower ledge b.

In advertising and display work, the number of sizes of type faces required above 36 pt. is comparatively few, so that an assortment comprising the four selected sizes shown in Figs. 8 and 9, namely, 42 pt., 48 pt., 60 pt., and 72 pt., is quite sufficient to meet the demand. The blocks D⁴ and D⁵ are, therefore, provided in the upper series with but four steps d (not including the special step d²) and in the lower series with but four steps d¹, the adjusting plate D⁶ (see Fig. 4) serving as the lowermost step of the latter series. Of course, the number could be increased or decreased if desired to give a greater or less range in the sizes of fonts handled. No special attention is necessary with fonts between 72 pt. and 144 pt., since the upper series of steps will take care of all conditions regardless of size.

In order that the control rod J of the "vise automatic" may be actuated as required in any adjusted position of the blocks D⁴, D⁵, there is employed a third stepped block D⁸ carried by the plate D⁶ and provided with upper and lower series of steps d³, d⁴ and a special step d⁶, duplicating the series of steps d, d¹ and the special step d² of the blocks D⁴, D⁵. The block D⁸ is hingedly mounted at the back in suitable bearings rising from the plate D⁶ and normally rests at the front upon the upper end of the rod J (Fig. 4).

As the plate D⁶ is adjusted to bring any selected pair of steps of the blocks D⁴, D⁵, beneath the banking screws B¹⁰ of the transporter, the corresponding step of the block D⁸ will be positioned directly above the rod J, so that the third screw B¹¹ in the overhead flange B² of the transporter B will depress the block D⁸, and thereby actuate the rod J, when the transporter is arrested in casting position by the banking of the screws B¹⁰ upon the blocks D⁴ and D⁵.

The plate D⁶ (see Figs. 4 and 5) is adjusted by means of a small knob or handle D⁹ mounted on an elongated extension of the block D⁴, and the plate is held in its adjusted positions by a spring latch or detent D¹⁰ pivotally mounted on the vise cap D¹ and arranged to engage in one or another of a series of notches d⁵ formed in the contiguous edge of said extension. The notches d⁵, nine in number (four for the lower series of steps d¹ and five for the upper series of steps d, including the

extra step d^2), are spaced apart a distance equal to that between the adjacent steps and (see Fig. 5) are marked in points to correspond to the various fonts of matrices employed, being adapted 5 when engaged with the detent D^{10} to indicate the corresponding adjustments of the banking blocks D^4 , D^5 and D^8 . For example, when the banking blocks are located in the adjusted position shown in Fig. 5 with the detent D^{10} engaged 10 with the 72 pt. notch for the lower series of steps d^1 , the composed line should comprise the special 72 pt. matrices, and the special mold L^3 should be employed in connection therewith so as to produce an L-shaped slug as in Fig. 31. If now 15 the slide should be adjusted to bring, say, the notch marked "reg." (meaning "regular") for the step d^2 opposite the detent D^{10} , as indicated by the dotted lines in Fig. 4, the setting of the parts would involve the use of the regular matrices Y with the regular mold L^2 , the matrices being supported at the normal lower level or the 20 normal upper level in the transporter B . In like manner, the detent D^{10} may be engaged in any one of the other notches d^5 to accommodate 25 a selected font of the corresponding size.

Line clamping vice jaws and justifying devices

Before the mold disc A is advanced preparatory to the casting operation and irrespective of 30 the level at which the transporter B is arrested, the matrix line is clamped tightly between the vise jaws C^1 , C^2 and positioned thereby endwise so as to register properly with the end walls l^2 of the mold slot. This operation is effected by a 35 vertical reciprocatory wedge bar M through the medium of a short horizontal slide rod against which the left-hand jaw C^1 abuts.

The rod C^3 is mounted in fixed bearings D^{11} , D^{12} and provided between said bearings with a 40 rigid block or collar C^4 . The upper end of the bar M is positioned between the bearings D^{11} and the block C^4 , and has an elongated slot m through which the rod C^3 extends. The side face of the bar M opposed to the bearing D^{11} is straight or 45 vertical, while its other face, that opposed to the block C^4 , is inclined upwardly to accord with the similarly inclined face of said block. As shown in Fig. 18, the block C^4 is held resiliently engaged with the bar M by a compression spring C^5 seated 50 in the bearing D^{12} and serving also to hold the bar against the bearing D^{11} . The jaw C^1 (see Fig. 5), moreover, is provided with a compression spring mounted in a block secured to the vise frame D and which holds the jaw resiliently 55 against the rod C^3 .

When the bar M is raised, the jaw C^1 is forced 60 positively thereby to the right or toward the opposing jaw C^2 , whereas when the bar is lowered, the jaw C^1 is forced to the left or returned to its original positions by resilient means not shown.

The bar M (see Fig. 1) is operated from the cam shaft R by means of a fore-and-aft lever M^1 , which is connected to the lower end of the bar by 65 an intermediate link M^2 . The upward movement of the bar M (in the present instance a positive one) is limited by a stop screw m^1 (Fig. 1), which is arranged in the vertical path of the lever M^1 , and hence the jaw C^1 is always moved 70 a definite distance by the bar M so as to locate the end matrices of a properly composed line, positioned between the two clamping jaws, in registry with the end walls l^2 of the mold slot. If the line is of proper length, the movement 75 of the left-hand jaw C^1 will be imparted by the

line to the right-hand jaw C^2 , which under such circumstances is adapted to yield toward the right against the tension of a spring C^7 which normally holds it toward the left against a fixed stop D^{14} (see Fig. 5), and which offers the resistance required for the justification of the line. In yielding, the jaw C^2 is adapted to actuate a safety pump stop lever common to the commercial linotype machines and which when actuated permits the cycle of operation to proceed, the active mold being moved up against the matrix line and the pot plungers allowed to descend by action of the spring E^2 hereinbefore mentioned. If the pump stop lever is not actuated by the yielding of the jaw C^2 , the casting operation cannot take place. The line clamping vise jaws and justifying devices are more fully described and claimed in my co-pending divisional application, Serial No. 654,558, filed January 31st, 1933.

Mold locating devices

As the mold approaches the composed line, a pair of studs a^1 projecting forwardly at diametrically opposite points from the face of the disc A are caused to enter corresponding sockets 100 formed in hardened blocks D^{17} secured to the vise frame D . The disc A and molds carried thereby are thus definitely located on the vise frame D with the side walls of the active mold horizontal and parallel to the base line of the matrices 105 clamped between the jaws C^1 , C^2 . This latter operation insures the proper alinement of the mold slot with the matrix characters, which have already been alined with one another in the line transporter, and the latter accurately located in 110 a truly horizontal position on the vise frame, and thus prepares the parts for the casting of the slug, which immediately follows.

When casting from the regular matrices Y and Y^1 , the pressure of the lockup or forward 115 thrust of the active mold will be directed against the clamping jaws C^1 , C^2 , as well as against the line, but the jaws under such conditions (see Fig. 14), are properly supported by the ledge b and shoulder b^1 of the transporter B . When 120 casting from the special matrices X or Z , the forward thrust of the mold is taken solely by the matrix line.

Pump lever support

It may be mentioned at this point that, as an additional feature of the invention, the pivot rod E^3 for the pump lever E^4 is extended and provided (see Fig. 2) with an outboard bearing E^6 rising from the upright side bracket T^1 of the 130 main frame. Such departure from the usual construction permits the spring E^2 for actuating the pump plungers to be located immediately adjacent the pump lever E^4 , whereby the point of application of its force is brought as close as 135 possible to the point of resistance. This arrangement is particularly advantageous in the present machine, since a long tension spring of greatly increased strength is required in producing slugs of the exceptionally large sizes herein 140 contemplated. This feature of the invention has been made the subject of my co-pending divisional application, Serial No. 654,556, filed January 31st, 1933.

Slug ejecting and related devices

After the casting of the slug, the pot E and mold disc A recede and the wedge bar M is lowered by the lever M^1 to release the matrix line, the left-hand jaw C^2 being moved out of contact 150

with the line, and the right-hand jaw C² being moved to its normal position against the stop D¹⁴. About this time, the cam track R² is moved out of engagement with the roller b⁷ of the upright arm B¹³ and allows the spring b¹¹ to close the gap between the nuts b¹³ and the lower bearing for the vertical rod B¹⁴, so that the transporter may be lifted by the cam R¹ through the lever B¹² to carry the line from between the jaws to the transfer level in registry with the table 2.

During these latter operations (all, of course, being performed in a certain predetermined order or sequence), the mold disc is given a three-quarter turn to carry the slug from the casting to the ejecting position, and the mold disc A is again advanced into engagement with a pair of banking blocks d⁸ secured to the vise frame D to bring the active mold into operative relation to the trimming knives G¹, G². With the parts in this position and the mold disc A firmly supported against the vise frame (Fig. 3), the ejector F is operated to push the slug out of the mold and past the cutting edges of the knives G¹, G², which trim the side faces of the slug and bring it to accurate size.

To support the disc A against angular displacement during the slug ejecting operation, it is provided with a second pair of studs a² (corresponding to the studs a¹ Fig. 24) which at the time engage in sockets formed in the blocks D¹⁷ secured on the vise frame.

When the mold disc A is moved forward the second time for the slug ejecting operation, one of the studs a thereon engages the actuating plunger J³, which would, unless means were otherwise provided, displace the control rod J of the vise automatic and bring about the stoppage of the machine. To avoid such occurrence, there is employed a small fore-and-aft rocking lever J⁴ pivoted to a bracket J⁵ fast to the vise frame D and arranged with its rear arm engaging upon a pin j¹ or lug projecting laterally from the lower end of the rod J. The lever J⁴ is actuated by a shoe J⁶ fastened to the body portion of the transporter B and arranged to engage said lever when the transporter has attained a certain intermediate level in its ascent from the casting position. In order to hold the transporter at such intermediate level until the slug ejecting operation is completed, the cam R¹ for operating the transporter is formed with a concentric portion r, which is adapted to engage the roller b⁷ of the upright lever B¹³ soon after the transporter starts to ascend.

55   *Slug trimming knives*

The right-hand knife (not shown) is carried by a block G³ slidably mounted in a fixed supporting frame G⁴, whereby the knife may be adjusted to and fro and set in different predetermined distances from the opposing knife G¹. A pair of compression springs mounted in the block tend constantly to move the block and consequently the knife G² in one direction away from the knife G¹, and a rotatable disc G⁶ is provided to adjust the block against the tension of said springs in the opposite direction.

The disc G⁶, according to the present invention, is formed with a spiral-shaped outer edge or periphery g¹ and is mounted to rotate on an axis disposed at right angles to the direction of movement of the knife G² (Fig. 1). A handle G⁹ is provided for rotating the disc G⁶, which is adapted when turned clockwise to move the knife G² positively toward the knife G¹ and when

turned anti-clockwise to permit the knife to be moved by the springs, before mentioned, away from the said knife G¹.

The knife G² may thus be adjusted to different positions according to the angular position of the disc G⁶, so as to register properly with the outer casting surface of the particular mold in use. The range of adjustment of the knife G² is from 6 pt. to 72 pt. to correspond with the range of adjustment of the special mold L⁴, and of course with that of the regular molds L¹, L².

80

85

90

95

A circular scale for indicating the adjusted positions of the knife G² may be secured concentrically to the front face of the disc G⁶, and arranged to be read in conjunction with a spring latch or detent employed to lock the disc against rotation. The detent is held normally under the tension of a spring (not shown) in engagement with one or another of a series of holes or apertures formed in the disc and disposed at predetermined points around the outer edge of the scale G¹⁰.

When it is desired to adjust the knife G², the detent is retracted to unlock the disc G⁶ by means of a small knob G¹³ arranged conveniently adjacent the handle G⁹, so that both adjustments may be effected by one hand.

The disc G⁶ is also provided with a series of hardened studs or set screws arranged around the spiral edge of the disc and disposed at points diametrically opposite the detent holes. The studs not only afford desirable banking points for the block carrying the knife G², but, being capable of individual adjustment, insure accuracy and precision in the adjustments of the knife G².

Unlike the right-hand knife G², on the other hand the left-hand knife G¹ is not adjustable, since it is intended to register as usual with the fixed inner casting surfaces or constant line of the molds. According to the present invention, however, it is movable bodily at will from its active position so as to stand out of the path of L-shaped slugs such as Q and Q⁵, whose top portions extend inwardly of or overlap the inner casting surfaces of the mold as before described.

In the preferred embodiment illustrated (see Fig. 1), the knife G¹ is carried by a broad vertically disposed block (not shown) slidably mounted in the vise frame D and operable from a rock shaft G¹⁵ through the medium of a horizontally disposed rod G¹⁶ and a cam G¹⁷ keyed to said shaft G¹⁵, against which one end of the rod G¹⁶ abuts. The rod G¹⁶ is anchored at its inner end to the block and is provided at its outer end adjacent the cam G¹⁷ with a spring (not shown) tending to move the knife G¹ toward the left to its inactive position.

The cam shaft G¹⁵ is mounted in a fixed bracket G¹⁹ and is provided with a crank handle G²⁰ by which it may be turned through 180° in opposite directions to rotate the cam G¹⁷ and move the knife block to and fro in the vise frame. When the crank handle is turned in a clockwise direction, the knife G¹ is moved positively by the cam G¹⁷ toward the right to its active position; and when the position of the crank handle is reversed, the knife G¹ is moved by the spring toward the left to its inactive position as determined by the contact of the rod G¹⁶ with the low portion of the cam G¹⁷.

130

135

140

145

With the foregoing improved trimming mechanism, slugs of the smaller sizes cast in the regular molds L¹, L², as well as those of the larger sizes cast in the special mold L⁴, are brought to

150

accurate size by the knives G^1 , G^2 as they are ejected. On the other hand, slugs of the overhanging type cast in the mold L^3 , while not trimmed, may be freely ejected by the retraction 5 of the knife G^1 . Moreover, as a result of the particular manner in which the right-hand knife is adjusted, a wide range is permitted with the use of a simple and compact arrangement of the parts. The slug trimming knives, the 10 tails of their mounting, and the operating mechanism therefor are more fully described in my co-pending divisional application, Serial No. 654,557, filed January 31st, 1933.

15 *Slug galley and delivery devices*

As the slugs are ejected from the mold, they are adapted to drop endwise into the receiving end of a vertically disposed chute H arranged directly beneath and in line with the knives 20 G^1 , G^2 . The knives serve to guide the slugs sideways as they enter the chute, and a thin yielding plate H^1 , restrains them against forward displacement. The plate H^1 (see Figs. 2 and 3) is hinged at its upper end on a pin h projecting 25 from the supporting block for the right-hand knife G^2 and is held resiliently in a vertical position against the body of said knife by a small torsion spring (not shown).

Slugs entering the chute H are conducted 30 downwardly and forwardly thereby and delivered into an elevator or conveyor H^2 , which latter is attached through an intermediate bracket H^3 to the lower end of the elongated body portion B^1 of the transporter B . The chute H (see Figs. 35 2 and 3) is U-shaped in cross-section and the side walls h^2 thereof are slightly lower than the height of the special molds L^3 and L^4 , so that the overhanging top portions of slugs such as Q and Q^5 may overlap, and thus receive support 40 by, the adjacent side wall h^2 as the slugs pass along the chute. The plain or ribbed slugs such as Q^2 are properly guided by the side walls h^2 , which are spaced far enough apart to accommodate slugs of the maximum thickness.

45 When the transporter is in casting position (Fig. 2), the elevator H^2 stands below the chute H , while when the transporter is in its upper or receiving position (Fig. 1), the elevator stands above the chute in registry with the galley S . However, when the transporter is momentarily arrested at its intermediate level as shown in 50 Fig. 3, the elevator H^2 is adapted to register with the discharge end of the chute H so as to receive the individual slugs as they pass therefrom, the concentric portion r of the cam R^1 being of sufficient extent to give ample time for a slug to be ejected from the mold and to pass through the chute into the elevator H^2 .

55 The elevator H^2 (see Figs. 3 and 22) is provided with an outer side wall H^4 formed with a pair of notches h^3 and is closed at the other side by a fixed guard plate S^2 depending from one of the brackets S^1 before mentioned and which support the galley S on the vise frame D . The elevator is also provided with a front end wall H^5 lined with a buffer of some pliable material to prevent damage to the slugs as they slide into the elevator from the chute H . The slugs, as they are individually cast, are therefore transported 60 from the lower level of the delivery chute H to the higher and more convenient level of the galley S .

70 As the slugs attain this higher level, they are shifted from the elevator H^2 sidewise and stacked 75 in the galley S by an L-shaped lever O , the latter

(see Figs. 22 and 23) being hinged at its upper end to the vise cap D^1 and arranged so that its lower arm O^1 , which projects forwardly over the receiving end of the galley, may be swung to carry a pair of integral depending slug engaging fingers o through the notches h^3 across the elevator H^2 (Fig. 3).

80 The lever O is operated against the tension of a spring O^3 anchored to the vise frame D from a long narrow vertically disposed cam plate O^2 , fastened to the transporter slide B^1 , through the medium of a pawl O^4 pivoted to the lever O . The active stroke of the lever O is effected by the spring O^3 and is limited by a stop pin o^1 mounted in a small bracket o^2 secured to the vise cap D^1 . The pawl O^4 projects laterally from the lever O into the vertical path of the cam plate O^2 and is limited in its pivotal movements by a pair of pins o^3 , o^4 located adjacent its pivotal axis.

85 When the machine is at rest, the parts occupy the position shown in Fig. 1, the pawl O^4 being sustained by the pin o^4 with its nose or free end disposed directly below the lower end of the cam plate O^2 , the lever O being held by the spring O^3 against the stop pin o^1 , and the elevator H^2 being positioned in registry with the galley S . As the transporter descends to the casting position, the cam plate O^2 , by its engagement with the pawl O^4 , swings the lever O to the right so as to carry the lower arm O^1 thereof across the 95 elevator H^2 and locate it in the retracted position shown in Fig. 22. During the upward or return movement of the transporter, the lever O is caused to maintain this retracted position until the transporter approaches its uppermost level, at which time the recess o^5 located immediately 100 adjacent the lower end of the cam plate O^2 is adapted to engage the pawl O^4 . As a result of such engagement and as the transporter continues to rise, the pawl O^4 is first swung upwardly into contact with the stop pin o^3 and then caused to leave the recess o^5 and clear the lower 105 end of the cam plate as the transporter completes its upward movement. In the meantime the elevator H^2 has been brought into registry with the 110 galley S , and the slug engaging fingers o of the stacker arm O^1 stand opposite the recesses h^3 of the elevator. Consequently, when the spring O^3 (upon being freed by the pawl O^4) swings the 115 lever O toward the left or back to its original 120 position against the stop o^1 , the fingers o are caused to engage the slug now deposited in the 125 elevator H^2 and shift it into the galley S .

130 *Safety devices*

130 Reference is now directed particularly to Figs. 17 to 21 inclusive, which illustrate in detail certain safety devices employed for preventing the casting operation whenever through carelessness or oversight the selection of a mold or the setting 135 of the transporter arresting blocks do not correspond to the matrices in use. These safety devices act to arrest the transporter at abnormal levels to bring about a stoppage of the machine by failing to depress the vise automatic control rod J .

140 An instance of an improper adjustment of the parts may be as follows: Suppose that, when a line of regular matrices is transported to the casting position, one of the special molds L^3 , L^4 , D^4 , D^5 , were improperly adjusted, say, to bring 145 a pair of steps, which are lower than the ones marked "reg.", into line with the banking screws B^{10} of the transporter. In either case, damage to the matrices and adjacent parts or a "front 150

squirt", or both, would result when the mold is advanced from the rear against the line and the pot plungers operated.

To avoid such occurrences in the particular instances noted, the auxiliary back plate B^7 (which it will be remembered must be attached to the transporter for the use of the regular matrices) is provided with a vertically disposed stop plate U , which is arranged to engage the safety members L^8 and L^9 of the regular and special molds, respectively. The plate U (see Figs. 15 and 19) is hinged at its upper end between a pair of lugs projecting from the rear face of the auxiliary plate B^7 and is inclined rearwardly from top to bottom so that its lower edge is in line with the safety members L^8 or L^9 when the corresponding molds are in use. A small compression spring u , arranged between the plate B^7 and the stop plate U , holds the latter in its inclined position but permits it to yield under normal conditions as the mold disc A moves forwardly. The movement of the stop plate U toward the rear is limited by a stop pin u^1 mounted thereon and provided with a head u^2 , seating in a recess u^3 formed in the back plate B^7 .

Assuming now that the stepped banking blocks D^4 , D^5 are properly adjusted when a line of regular matrices Y is supported at the lower level in the transporter B , that is, with the extra "reg." step d^2 or the uppermost step d located beneath the banking screws B^{10} of the transporter, and that the regular mold L^2 is selected (which would represent a correct setting of the parts): the stop plate U (as shown in Fig. 14) will then fail to engage the safety member L^8 of said mold as the transporter comes to rest, and the rod J will therefore be depressed to permit the casting of the slug in the regular way. However, if a special mold L^3 or L^4 should happen to be in use, (which would represent an incorrect setting of the parts), the transporter would be arrested in its descent at the abnormal level shown in Fig. 18 by the engagement of the stop plate U with the safety member L^9 , the latter (as may be noted, Figs. 24 and 25) being longer than the safety member L^8 of the correct mold L^2 . As a result, the banking screw B^{11} of the transporter does not engage the hinged block B^8 which operates the rod J , and hence the machine will be automatically stopped in the manner before described. The condition would be the same if the banking blocks D^4 , D^5 were improperly adjusted to bring into play a step lower than the step d^2 , since then the stop plate U would engage the safety member L^8 of the regular mold L^2 before the banking screw B^{11} reached the hinged block D^8 and thus prevent the depression of the rod J .

It so happens, as may be observed by referring to Fig. 17, that the second step from the top of the upper series d , (which, incidentally, determines the level at which the 60 pt. special matrices should be supported), is slightly higher than the extra "reg." step d^2 and such that, irrespective of the stop plate U , the casting operation would take place if this 60 pt. step should be selected by an improper adjustment of the stepped banking blocks when the regular matrices and a regular mold are in use. Such a contingency is avoided by means of a fore-and-aft stop member V mounted to slide transversely in the transporter head B^3 and controlled in its movements by the detachable back plate B^7 of the transporter.

When the plate B^7 is attached to the transporter, the front end of the stop member V is projected forwardly into a position directly over the

vise cap D^1 so as to cooperate with the auxiliary banking block V^1 carried by the adjusting slide D^6 ; whereas, when the back plate is removed from the transporter, the opposite end of the stop member V , for reasons about to be pointed out, is projected rearwardly into a position to cooperate with the safety member of the active mold.

The stop member V (see Fig. 19) is provided with a spring V^2 , which is held under compression between the back plate B^7 and a retaining block V^3 fixed to the transporter head B^3 , and which, in the absence of the back plate, is adapted to maintain the stop member resiliently in its rearward position. At such times, the front end of the stop member is out of the way of the vise cap D^1 (as indicated by the dotted lines in Figs. 6 and 7) and is accurately located in such position by means of a stop pin v . The retaining block V^3 is mounted in the front face of the transporter head B^3 and fits in a longitudinal recess v^1 , formed in the upper side of the stop member and wherein the spring V^2 is located. In its lower side, the stop member V is also formed with a cut or recess v^2 extending transversely therethrough and which when the member occupies its rearward position will afford clearance for the upper extensions z^3 and z^2 of the special matrices X and Z as the latter are inserted into or removed from the transporter.

Fig. 17 illustrates clearly the manner of resting the transporter before it can actuate the rod J when the auxiliary back plate B^7 is attached and the slide D^6 is improperly adjusted to bring the 60 pt. step beneath the banking screws B^{10} , giving rise to the contingency above referred to. The stop member V , through the presence of the back plate B^7 , occupies its forward position and the block V^1 under the stated adjustment of the slide D^6 is positioned directly in the path of the said stop member, so that the transporter in its descent will be arrested by the contact of these parts at the abnormal level shown.

The stop member V is also adapted, when the back plate B^7 is removed, to arrest the transporter at the same abnormal level by its engagement at the rear with the safety members L^8 of the regular molds L^1 and L^2 , if by mistake one or the other of these molds is selected instead of a special mold L^3 or L^4 , it being remembered that the use of said back plate B^7 is devoted entirely to the regular matrices Y and Y^1 .

While the safety members L^9 associated with the special molds, as well as the safety members L^8 associated with the regular molds, occupy corresponding positions on the disc A , the stop member V is not allowed to contact with the members L^9 on account of the recesses l^{11} formed therein, see Figs. 24 and 25. In other words, the recesses l^{11} are vertically aligned with the stop member V (as depicted in Fig. 4), so that the transporter may descend to any of the casting levels determined by the stepped banking blocks D^4 , D^5 when a special mold and not a regular mold is properly selected.

If the level of the transporter happens to be one determined by the lowermost steps d^1 (as shown in Fig. 6), the stop member V will be pushed forwardly against the tension of the spring V^2 as the mold is moved into contact with the line; and to permit such forward movement, the vise cap D^1 and also the rear gib D^7 are cut away as at v^3 to provide the required clearance space for the stop member V .

Another set of safety devices is provided to prevent the actuation of the rod J (and the

consequent casting operation) when the regular matrices Y stand at the upper level on the ledge b⁶ in the transporter B and the stepped banking blocks are improperly adjusted to bring the uppermost step d beneath the banking screws B¹⁰, it being understood that by such an adjustment of the said banking blocks the transporter will be arrested at the normal auxiliary level and therefore that the matrices therein should be composed in the transporter at the normal lower level on the ledge b, so as to bring their lower projecting ears in registry with the upper groove b⁵ of a regular mold. A similar condition is presented in the commercial linotype machines which make use of a so-called "simple two-letter device", and various schemes have been proposed to overcome the difficulty involved.

According to the present invention, however, it is proposed to stop the descent of the transporter by means actuated by the matrices themselves. Such means (as best shown in Figs. 20 and 21) consists of a hammer-shaped dog or interponent W mounted horizontally in a transverse recess b¹⁸ formed in the front wall B⁵ of the transporter B. The dog W is provided with a head portion w arranged at the receiving end of the transporter B and it is pivoted on a vertical axis w¹ at a point remote from the head, so that the latter may be projected forwardly beyond the front face of the wall B⁵. The head w of the dog is extended rearwardly and formed with a beveled cam surface w², which in the normal position of the dog is disposed in the path of matrices Y as they are delivered horizontally to the transporter at the upper or auxiliary level.

To cooperate with the dog W, the adjusting slide D⁶ for the stepped banking blocks D⁴, D⁵ and D⁸ is provided with a second auxiliary banking block W¹, which (as shown in Fig. 5) is arranged directly behind the stepped block D⁵ and adapted when the slide is adjusted to the position shown in Fig. 18, with the uppermost steps d of the blocks D⁴, D⁵ beneath the screws B¹⁰, to be vertically aligned with the head w of the dog W. At such times, therefore, if matrices happen to be transferred from the table 2 or by hand into the transporter for support upon the upper rail b⁶, the head of the dog W will be cammed forwardly by the matrices and caused to engage the banking block W¹ when the transporter descends, thus arresting the transporter in the abnormal position shown in Figs. 18 and 20.

The dog W is held yieldingly in both its active and inactive positions by a vertically disposed spring detent w³ mounted in the front wall of the transporter B and engaging in corresponding shallow recesses w⁴ formed in the upper face of the head of the dog. While the dog W may be returned to its normal position within the transporter by hand, this operation is herein effected automatically, under a different adjustment of the slide D⁶, by the simple expedient of a beveled cam surface w⁵ formed at the bottom of a notch W² in the vise cap D¹ (see Figs. 5 and 20).

As a result of the safety equipment above described, the machine is substantially fool-proof, notwithstanding the different forms of matrices and molds employed.

No special precautions are necessary when the special matrices are used with the special molds, since no damage to the parts can result if a mold of the wrong size or kind is selected or the stepped blocks improperly adjusted. The rear wall B⁵ of the transporter head, by the face to face engagement with the mold, will prevent metal

squirts, and the worst that can happen is the casting of an imperfect slug.

Conclusion

It is believed that the operation of the various parts will be clear from the description given throughout the detailed specification, and especially in view of the introduction under the heading "General organization and operation of machine". For the sake of brevity, therefore, no further description will be attempted here.

Having thus described my invention, what I claim is:

1. In a slug casting machine adapted to be equipped with matrices having casting edges devoid of mold engaging ears and formed in said edges with intaglio characters of different heights located thereon for common base alinement, the combination of a slotted mold whose contiguous face is adapted to contact with the casting edges of the matrices, means for supporting a composed line of matrices in casting relation to the mold in one or another of a series of different transverse positions according to the height of the matrix characters in use, and means for properly alining the matrix characters with the mold slot notwithstanding the absence of mold engaging ears on the matrices.

2. In a slug casting machine adapted to be equipped with matrices having casting edges devoid of mold engaging ears and formed in said edges with intaglio characters of different heights located thereon for common base alinement, the combination of a slotted mold whose contiguous face is adapted to contact with the casting edges of the matrices, and comprising a fixed body portion and a cap portion adapted to be set at a distance from the body portion to accord with the height of the matrix characters in use, means for supporting a composed line of matrices in casting relation to the mold in one or another of a series of different transverse positions according to the position of the cap portion, and means for properly alining the matrix characters with the mold slot notwithstanding the absence of mold engaging ears on the matrices.

3. In a slug casting machine adapted to be equipped with matrices having casting edges devoid of mold engaging ears and formed in said edges with intaglio characters of different heights located thereon with reference to a common datum line passing through the bases of the characters, said characters being formed in the bottom of recesses cut through the edges of the matrices, and said recesses at one end terminating different distances from said datum line in different fonts to accommodate the different length descenders of the lower case characters in said fonts, the combination of a mold presenting a broad flat face for engagement with the casting edges of the matrices and having a slot of a width less than the height of the matrix characters, and means for supporting a composed line of matrices in casting relation to the mold in one or another of a series of different transverse positions to locate the recesses of the matrices of a given font at that end adjacent the datum line in register with one of the walls of the mold slot; whereby L-shaped slugs may be produced with body portions of uniform thickness and overhanging top portions of different widths bearing upper case and lower case characters of different heights.

4. A combination as in claim 1, wherein the matrix characters stand inverted on their casting

- edges and wherein the mold occupies a horizontal position during casting, characterized by the fact that the composed line is presented to the mold by a vertically movable transporter adapted to support the matrices with their characters in base alinement, and means for positioning the transporter in casting relation to the mold at one or another of a series of different levels according to the height of the matrix characters in use. 5 80
- 10 5. A combination as in claim 1, wherein the matrix characters stand inverted on their casting edges and wherein the mold occupies a horizontal position during casting, characterized by the fact that the composed line is presented to the mold by a vertically movable transporter adapted to support the matrices with their characters in base alinement, means for positioning the transporter in casting relation to the mold at one or another of a series of different levels according to the height of the matrix characters in use, and means for locating the line transporter and mold in true horizontal positions during the slug casting operation. 15 85
- 20 6. A combination as in claim 1, wherein the matrix characters stand inverted on their casting edges and wherein the mold occupies a horizontal position during casting, characterized by the fact that the composed line is presented to the mold by a vertically movable transporter adapted to support the matrices with their characters in base alinement, a vise frame wherein the transporter is movable, means for positioning the transporter in casting relation to the mold at one or another of a series of different levels according to the height of the matrix characters in use, means mounted on said vise frame for locating the transporter in a truly horizontal position during casting, and means also mounted on said vise frame for locating the mold in a truly 25 90
- 30 40 horizontal position during casting. 95
7. A combination as in claim 1, wherein the matrix characters stand inverted on their casting edges and wherein the mold occupies a horizontal position during casting, characterized by the fact that the composed line is presented to the mold by a vertically movable transporter adapted to support the matrices with their characters in base alinement, and an adjustable stepped banking block for arresting the transporter in casting relation to the mold at one or another of a series of different levels according to the height of the matrix characters in use. 45 100
- 50 8. A combination as in claim 1, wherein the matrix characters stand inverted on their casting edges and wherein the mold occupies a horizontal position during casting, characterized by the fact that the composed line is presented to the mold by a vertically movable transporter adapted to support the matrices with their characters in base alinement, and a pair of duplicate adjustable stepped banking blocks, one arranged at each end of the transporter head, for arresting the transporter in casting relation to the mold at one or another of a series of different levels according to the height of the matrix characters in use, and means for holding the transporter under pressure down upon the banking blocks during casting to insure the horizontal alinement of the composed line with the mold slot. 55 105
- 60 70 9. In a slug casting machine adapted to be equipped with matrices formed in their casting edges with intaglio characters of different heights located thereon for common base alinement, the combination of a slotted mold whose contiguous face is adapted to contact with the casting edges 65 110
- 75 of the matrices, means for presenting a composed line of matrices to the mold in one or another of a series of different transverse positions according to the height of the matrix characters in use, and means for alining the composed line of matrices with the mold other than by their mutual engagement. 80
10. In a slug casting machine adapted to be equipped with matrices formed in their casting edges with inverted intaglio characters of different heights located thereon for common base alinement, the combination of a slotted mold adapted to be located in a horizontal position during casting, a vertically movable transporter wherein a composed line of matrices is supported with their characters in base alinement, means for positioning the transporter in casting relation to the mold at one or another of a series of different levels according to the height of the matrix characters in use, and means independent of the matrices and the mold for alining the matrix characters with the mold slot. 85
11. In a slug casting machine, the combination of a slotted mold adapted to occupy a horizontal position during casting, a vertically movable transporter wherein a composed line of matrices is supported against vertical displacement and operable to position the composed line in casting relation to the mold, a pair of banking members carried by the transporter head, one at each end thereof, and adapted to arrest the transporter in said casting relation, a relatively fixed horizontal surface with which the transporter banking members contact, and means for holding the transporter down under pressure with its banking members in contact with the fixed horizontal surface; whereby the composed line is alined horizontally with the mold slot without engagement of these parts. 90
12. In a slug casting machine adapted to be equipped with matrices having intaglio characters of different heights located thereon for common base alinement and comprising upper case and lower case characters, the combination of two slotted molds, either one of which may be brought into use as desired, and means for presenting a composed line of matrices to one of the molds when in use in one or another of a series of different transverse positions according to the height of the upper case matrix characters, and to the other mold when in use in one or another of a second series of different transverse positions according to the height of the descendents of the lower case matrix characters. 100 105
13. In a slug casting machine adapted to be equipped with matrices formed in their casting edges with inverted intaglio characters of different heights located thereon for common base alinement and comprising upper case and lower case characters, the combination of two slotted molds, either one of which may be brought into use as desired, a vertically movable transporter wherein a composed line of matrices is supported with their characters in base alinement, and means for positioning the transporter in casting relation to one mold when in use at one or another of a series of different levels according to the height of the upper case matrix characters, and to the other mold when in use at one or another of a second series of different levels according to the height of the descendents of the lower case matrix characters. 110 115
14. In a slug casting machine adapted to be equipped with matrices formed in their casting edges with inverted intaglio characters of differ- 120 125
- 130 135
- 140 145
- 150

- ent heights located thereon for common base alinement and comprising upper case and lower case characters, the combination of two slotted molds, either one of which may be brought into 5 use as desired, a vertically movable transporter wherein a composed line of matrices is supported with their characters in base alinement, and an adjustable banking block for arresting the transporter in casting relation to the slotted mold, said 10 block being formed with upper and lower series of steps, one series for each mold, the steps of the upper series varying in height according to the height of the upper case characters of the matrices in different fonts, and the steps of the lower series varying in height according to the height 15 of the descenders of the lower case characters of the matrices in different fonts.
15. A combination as in claim 12, wherein the two molds each comprise a body portion and 20 a cap portion and are mounted on a rotatable disc which is adjustable to bring either mold into use, and characterized by the fact that the fixed body portions of both molds have their casting surfaces located at a common distance from the 25 axis of the disc, and that the cap portion of one mold is adjustable toward and from the body portion to vary the width of the mold slot according to the height of the matrix characters in use, while the cap portion of the other mold 30 is fixed with reference to the body portion so as to provide a mold slot of a single given width irrespective of the height of the matrix characters.
16. In a slug casting machine, the combination 35 of two slotted molds, one for casting slugs with and the other for casting slugs without overhanging type-carrying portions, means for selecting either mold for use, and means whereby a composed line of matrices may be presented at one 40 station for cooperation with the first mold or at a different station for cooperation with the second mold.
17. In a slug casting machine adapted to be 45 equipped with matrices having characters of different heights, the combination of two slotted molds, one comprising a fixed body portion and an adjustable cap portion to vary the width of the mold slot according to the height of the matrix characters in use, and the other mold 50 comprising fixed body and cap portions spaced apart to provide a mold slot of a single given width irrespective of the height of the matrix characters in use, means for selecting either mold, and means whereby composed matrix lines 55 may be presented at different stations for cooperation with the first mold or at other different stations for cooperation with the second mold.
18. In a slug casting machine adapted to be 60 equipped with matrices formed in their casting edges with intaglio characters of different heights located thereon for common top alinement or with matrices formed in their casting edges with intaglio characters of different heights located 65 thereon for common base alinement, the combination of two slotted molds, one for cooperating with the top alinement matrices and the other for cooperating with the base alinement matrices, means for selecting either mold for use, and 70 means whereby a composed line of matrices may be presented at one station for cooperation with the first mold or at a different station for co-operation with the second mold.
19. In a slug casting machine adapted to be 75 equipped with matrices formed in their casting
- edges with intaglio characters of different heights located thereon for common top alinement or with matrices formed in their casting edges with intaglio characters of different heights located thereon for common base alinement, the combination of two slotted molds, one for cooperating with the top alinement matrices and the other for cooperating with the base alinement matrices, means for selecting either mold for use, and means whereby a composed line of matrices may be presented at one given station for cooperation with the first mold irrespective of the height of the matrix characters, or at one or another of several different stations for cooperation with the second mold according to the height of the matrix characters. 80
20. A combination as in claim 18, wherein each of the molds comprises a fixed body portion and an adjustable cap portion, and characterized by the fact that the fixed body portions of both molds present their casting surfaces in the same plane during casting. 85
21. A combination as in claim 18, wherein the mold for the top alinement matrices comprises a fixed body portion and an adjustable cap portion, while the mold for the base alinement matrices comprises fixed body and cap portions, the body portions of both molds presenting their casting surfaces in the same plane during casting. 90
22. In a slug casting machine adapted to be 105 equipped with matrices formed in their casting edges with intaglio characters of different heights located thereon for common top alinement or with matrices formed in their casting edges with intaglio characters of different heights located 110 thereon for common base alinement, the combination of three slotted molds, one for cooperating with the top alinement matrices, and the other two for cooperating with the base alinement matrices and differing as to form, means for bringing a selected mold into use, and means whereby a composed line may be presented at one given station for cooperation with the first mold or at other different stations for cooperation 115 with the other two molds. 120
23. In a slug casting machine, the combination of a slotted mold comprising a fixed body portion with a broad flat matrix engaging face and a plain flat casting surface and a cap portion spaced from the body portion and formed on its casting 125 surface with a plurality of core members projecting into the mold slot and separated by intermediate fore-and-aft grooves, and a line of matrices supported in casting relation to the mold, said matrices having their intaglio characters formed in the bottoms of recesses cut through the casting edges of the matrices, and said recesses registering at one end with the casting surface of the cap portion and extending beyond the casting surface of the body portion 130 along the broad flat face thereof; whereby there is produced a slug with a relatively thin body portion and a wide type-carrying portion supported at one side by ribs cast on the body portion and overhanging the body portion at the other side without support. 135
24. In a slug casting machine, the combination of a slotted mold comprising a fixed body portion with a broad flat matrix engaging face and a plain flat casting surface and a cap portion spaced from the body portion and formed on its casting 140 surface with a plurality of core members projecting into the mold slot and separated by intermediate fore-and-aft grooves, and a line of matrices supported in casting relation to the mold. 145
- 150

said matrices having their intaglio characters formed in the bottoms of recesses cut through the casting edges of the matrices, the recesses of some of said matrices registering at their opposite ends with the casting surfaces of the body and cap portions respectively, and the recesses of other of said matrices registering at one end with the casting surface of the cap portion and extending beyond the casting surface of the body portion 10 along the broad flat face thereof; whereby there is produced a slug with a relatively thin body portion and a wide type-carrying portion, a part of which latter portion is supported wholly by the body portion and ribs cast on one side thereof, 15 and a part of which is similarly supported but which overhangs the body portion at the other side without support.

25. In a slug casting machine, the combination of a slotted mold comprising a fixed body portion 20 with a broad flat matrix engaging face and a plain flat casting surface and a cap portion spaced from the body portion and formed on its casting surface with a plurality of core members projecting into the mold slot and separated by intermediate fore-and-aft grooves, and a line of matrices supported in casting relation to the mold, said matrices having intaglio characters of different heights located for common base alinement and formed in the bottoms of recesses cut 30 through the casting edges of the matrices, the recesses of all said matrices registering at one end with the casting surface of the cap portion, and said recesses at their opposite ends on different matrices terminating above, in register with, and 35 below the casting surface of the body portion, respectively.

26. In a slug casting machine, the combination of a slotted mold comprising a fixed body portion having a plain flat casting surface and a cap 40 portion spaced from the body portion and formed on its casting surface with a plurality of core members projecting into the mold slot and separated by intermediate fore-and-aft grooves, and a line of matrices supported in casting relation 45 to the mold, said matrices having their intaglio characters formed in the bottoms of recesses cut through the casting edges of the matrices, and said recesses at one end registering with the casting surface of the body portion and extending 50 beyond the casting surface of the cap portion along the matrix engaging face thereof; whereby there is produced a slug with a relatively thin body and a wide type-carrying portion supported partly by ribs cast on the body at one side, but 55 projecting beyond and overhanging the ribs at that side.

27. In a slug casting machine, the combination of a slotted mold having a fixed body portion and a cap portion adjustable toward and from the body portion to vary the width of the mold slot, a line of matrices formed in their casting edges with intaglio characters of a height greater 60 than the adjusted width of the mold slot, and means for presenting the matrix line to the mold at different levels determined by the adjusted position of the mold cap; whereby slugs may be produced with varying thicknesses of body and 65 varying widths of overhanging type-carrying portions.

28. In a slug casting machine, the combination of a slotted mold, a line of matrices supported in casting relation to the mold, said line including character-bearing matrices of different 70 lengths having their intaglio characters formed 75 in the bottoms of recesses cut through the cast-

ing edges of the matrices, the recess of a long matrix extending beyond the end of an adjoining short matrix, and a blank matrix situated between said long and short matrices to close that side of the recess in the long matrix.

29. A combination as in claim 23, wherein the matrices whose recesses extend beyond the casting surface of the mold body portion are longer than the other matrices and have their recesses extending beyond the ends of the adjoining short matrices, and characterized by the fact that the matrix line includes a blank matrix situated between each said long matrix and the adjoining short matrix to close that side of the recess in the long matrix.

30. A type casting matrix having its character bearing edge devoid of projecting ears and formed at the top with an upwardly extending lug of reduced width leaving a square alining surface on the top edge adjoining the character bearing edge.

31. A type casting matrix having its character bearing edge devoid of projecting ears and formed at the top with an upwardly extending lug of reduced width leaving a square alining surface 100 on the top edge adjoining the character bearing edge, and at the bottom with a square alining surface.

32. A type casting matrix of rectangular form, one of the side edges containing the character 105 impression, the bottom edge presenting a square alining surface, and the top edge having an upstanding rectangular lug leaving square alining surfaces on the top edge adjoining the side edges.

33. A type casting matrix having straight parallel side edges, one containing the character impression, and the other a rectangular notch whose upper wall provides a square alining surface.

34. A type casting matrix having straight parallel side edges, one containing the character impression, and the other a rectangular notch whose upper wall provides a square alining surface, and a top edge having an upstanding rectangular lug leaving square alining surfaces on 120 the top edge adjoining the side edges.

35. A series of matrices having intaglio characters of different heights and formed according to claim 30 characterized by the fact that the characters of all the matrices are located thereon with reference to a common datum line passing through the bases of the characters, and that said datum line is situated at the same distance from the alining surfaces throughout the series.

36. In a slug casting machine, the combination of a line of matrices of rectangular form, and a transporter wherein the matrix line is supported, said transporter comprising opposed parallel members to engage the matrices adjacent their opposite ends and hold them against endwise displacement.

37. In a slug casting machine, the combination of a line of matrices of rectangular form having lugs rising from their top edges, and a 140 transporter wherein the matrix line is supported, said transporter comprising parallel side walls between which the matrix lugs are positioned, and a supporting ledge upon which the matrices rest adjacent their lower edges.

38. In a slug casting machine, the combination of a line of matrices of rectangular form provided at their upper ends and at opposite edges with rectangular notches, and a transporter wherein the matrix line is supported, said 150

- transporter having a fixed ledge to support the matrices adjacent their lower ends, and shouldered portions fitting snugly in the notches at their upper ends.
- 5 39. A combination as in claim 38, characterized by the fact that the matrices are sustained in the transporter with their bottom edges resting on the fixed supporting ledge.
- 10 40. A combination as in claim 38, characterized by the fact that the matrices are notched in their non-character bearing side edges and are sustained in the transporter with the upper walls of said notches resting on the fixed supporting rail.
- 15 41. In a slug casting machine, the combination of a transporter comprising front and rear walls, and a line of matrices supported in said transporter with the casting edges of the matrices flush with the rear face of the rear wall of the transporter.
- 20 42. In a slug casting machine, the combination of a line of matrices, each having straight parallel front and rear edges devoid of projecting ears and formed at its top edge with an upstanding rectangular lug, and a transporter wherein the matrix line is supported, said transporter comprising front and rear walls between which the upstanding matrix lugs are positioned, and the rear wall of the transporter having its rear face flush with the casting edges of the matrices.
- 25 43. A combination according to claim 37 characterized by the fact that the transporter is adapted to be equipped with an auxiliary member to adapt it for the support of matrices formed with projecting ears on their side edges.
- 30 44. In or for a slug casting machine, a line transporter constructed for the support of matrices formed with or without projecting ears on their side edges.
- 35 45. In or for a slug casting machine adapted to be equipped with matrices having projecting ears on their casting edges or with matrices devoid of projecting ears on their casting edges, a line transporter provided with means for supporting matrices of both forms therein, said means being partly removable from the transporter in adapting it for the support of the earless matrices.
- 40 46. In or for a slug casting machine adapted to be equipped with matrices having projecting ears on their side edges or with matrices devoid of such projecting ears, a line transporter having a common supporting ledge for matrices of both forms and provided with means located permanently thereon for holding the matrices without projecting ears upon the supporting ledge, and auxiliary means adapted to be detachably applied to the transporter for holding the matrices with projecting ears upon the supporting ledge.
- 45 47. In or for a slug casting machine adapted to be equipped with relatively short matrices formed with projecting ears on their opposite side edges or with longer matrices devoid of projecting ears on their opposite side edges but formed at the top with upstanding lugs, a line transporter comprising fixed front and rear walls between which the upstanding lugs of the longer matrices are positioned, the front wall being provided with a fixed supporting ledge for matrices of both forms, and an auxiliary plate adapted to be detachably applied to the rear wall of the transporter and having a supporting ledge which, when the plate is applied, is located beneath the lower edge of the rear wall so as to engage beneath the upper ears of the shorter matrices.
- 50 48. A combination as in claim 47, wherein the front wall of the transporter is formed above the supporting ledge with two superposed grooves to receive the lower projecting ears of the shorter matrices when standing at an upper or lower level in the transporter, and said ledge forming the lower wall of the lower groove.
- 55 49. In a slug casting machine adapted to be equipped with matrices of two different forms, the combination of two slotted molds, one to cooperate with matrices of one form and the other with matrices of the second form, means for presenting a composed line of matrices to either selected mold, and safety means for preventing the casting operation when the mold and matrices do not correspond as to form.
- 60 50. In a slug casting machine adapted to be equipped with matrices of two different forms, the combination of two slotted molds, one to cooperate with matrices of one form and the other with matrices of the second form, a vertically movable transporter wherein a composed line of matrices of one form or the other is supported and operable to present the composed line in casting relation to the selected mold, and safety means for arresting the transporter at an inoperative or non-casting level when the mold and matrices do not correspond as to form.
- 65 51. In a slug casting machine adapted to be equipped with matrices of two different forms, the combination of two slotted molds, one to cooperate with matrices of one form and the other with matrices of the second form, an adjustable device to position the transporter at one level or another according to the form of the matrices, and safety means for preventing the casting operation when said transporter positioning device is improperly adjusted.
- 70 52. In a slug casting machine adapted to be equipped with matrices of two different forms, the combination of two slotted molds, one to cooperate with matrices of one form and the other with matrices of the second form, an adjustable device to position the transporter at one level or another according to the form of the matrices, and safety means for arresting the transporter at an inoperative or non-casting level when the arresting device is improperly adjusted.
- 75 53. A combination as in claim 50, characterized by the fact that the safety means therein referred to consist of arresting members of variant form associated with the respective molds, and two stop members carried by the transporter and arranged to engage said arresting members in the descent of the transporter, one of said stop members being active and the other inactive when matrices of one form are carried by the transporter, and vice versa when matrices of the other form are carried by the transporter.
- 80 54. A combination as in claim 50, wherein the transporter is equipped with an auxiliary section which is applied thereto when matrices of one form are supported therein, and which is detached therefrom when matrices of the other form are supported therein, and characterized by the fact that the safety means therein referred to consist of arresting members of variant form associated with the respective molds, and two stop members carried by the transporter and arranged to engage said arresting members in the descent of the transporter, one of said stop members being permanently mounted on the transporter, and the other being mounted on

- the auxiliary section so as to be applied to or removed from the transporter therewith.
55. A combination as in claim 50, wherein the transporter is equipped with an auxiliary section which is applied thereto when matrices of one form are supported therein, and which is detached therefrom when matrices of the other form are supported therein, and characterized by the fact that the safety means therein referred to consist of arresting members of variant form associated with the respective molds, and two stop members carried by the transporter and arranged to engage said arresting members in the descent of the transporter, one of said stop members being permanently mounted on the transporter, and the other being mounted on the auxiliary section so as to be applied to or removed from the transporter therewith, characterized by the fact that when the auxiliary section is applied to the transporter the stop member permanently mounted on the transporter is held out of engaging relation to the arresting members associated with the molds.
56. A combination as in claim 50, wherein the transporter is equipped with an auxiliary section which is applied thereto when matrices of one form are supported therein, and which is detached therefrom when matrices of the other form are supported therein, and characterized by the fact that the safety means therein referred to consist of arresting members of variant form associated with the respective molds, and two stop members carried by the transporter and arranged to engage said arresting members in the descent of the transporter, one of said stop members being permanently mounted on the transporter, and the other being mounted on the auxiliary section so as to be applied to or removed from the transporter therewith, characterized by the fact that when the auxiliary section is applied to the transporter the stop member permanently mounted on the transporter is held out of engaging relation to the arresting members associated with the molds, but under such conditions is positioned in engaging relation to a further arresting member carried by the adjusting device which determines the operative level of the transporter.
57. A combination as in claim 50, wherein the transporter is equipped with an auxiliary section which is applied thereto when matrices of one form are supported therein, and which is detached therefrom when matrices of the other form are supported therein, and characterized by the fact that the safety means therein referred to consist of arresting members of variant form associated with the respective molds, and two stop members carried by the transporter and arranged to engage said arresting members in the descent of the transporter, one of said stop members being permanently mounted on the transporter, and the other being mounted on the auxiliary section so as to be applied to or removed from the transporter therewith, characterized by the fact that in the normal relation of the parts the stop member carried by the auxiliary section is arranged to yield when the mold is brought into contact with the matrix line.
58. A combination as in claim 50, wherein the transporter is equipped with an auxiliary section which is applied thereto when matrices of one form are supported therein, and which is detached therefrom when matrices of the other form are supported therein, and characterized by the fact that the safety means therein referred to consist of arresting members of variant form associated with the respective molds, and two stop members carried by the transporter and arranged to engage said arresting members in the descent of the transporter, one of said stop members being permanently mounted on the transporter, and the other being mounted on the auxiliary section so as to be applied to or removed from the transporter therewith, characterized by the fact that in the normal relation of the parts the stop member carried by the auxiliary section is arranged to yield when the mold is brought into contact with the matrix line.
59. In a slug casting machine adapted to be equipped with regular two letter matrices formed with projecting ears or with special matrices devoid of projecting ears and having characters of different heights located for base alinement, the combination of a plurality of slotted molds, one to cooperate with the regular matrices, and others of different form to cooperate with the special matrices a mold carrier wherein the molds are mounted and adjustable at will to bring one mold or another into use, a transporter to carry composed lines of matrices to and from the casting position, an adjustable stepped banking block for arresting the transporter at different predetermined levels so as to locate lines of regular or lines of special matrices in proper casting relation to the corresponding molds, and safety means to prevent the casting operation when said banking block is improperly adjusted.
60. In a slug casting machine adapted to be equipped with regular two letter matrices formed with projecting ears or with special matrices devoid of projecting ears and having characters of different heights located for base alinement, the combination of a plurality of slotted molds, one to cooperate with the regular matrices, and others of different forms to cooperate with the special matrices, a carrier wherein the molds are mounted and adjustable at will to bring one mold or another into use, a transporter to carry composed lines of said matrices to and from the casting position, an adjustable slide, a stepped banking block carried by the slide for arresting the transporter at different predetermined levels so as to position the lines of regular or lines of special matrices in proper casting relation to their respective molds, and safety means for arresting the transporter at an inoperative or non-casting level when the stepped banking block is improperly adjusted or the active mold improperly selected.
61. A combination as in claim 60, including an auxiliary banking piece or lug carried by the adjustable slide, and a plate detachably connected to the rear face of the transporter for supporting the regular matrices therein, and characterized by the fact that the safety means therein referred to comprises a movable stop member mounted transversely in the transporter and adapted to occupy a forward position to cooperate with the auxiliary banking piece when the said plate is attached to the transporter and to occupy a rearward position to cooperate with the banking block associated with the mold for the regular matrices when the supporting plate is removed.
62. In a slug casting machine, the combination of a plurality of slotted molds differing in form, a carrier adjustable to bring one or another of said molds into use, a transporter for presenting composed lines of matrices to the active mold, a plurality of safety members of dif-

- ferent heights associated with the respective molds to prevent the presentation of matrix lines under abnormal conditions, and distinguishing means to insure the application of the safety members to the corresponding molds.
63. A combination as in claim 62, characterized by the fact that the said safety members are secured to the mold carrier at common points and that the distinguishing means therein referred to consists of lips or projections formed on the safety members and adapted to engage corresponding notches located at different points on the respective molds.
64. In a slug casting machine adapted to be equipped with regular two letter matrices formed with projecting ears, the combination of a mold adapted to cooperate with the matrices, a vertically movable transporter for presenting composed lines of the matrices to the mold and wherein the lines may be supported at a high or low level to locate either of their superposed characters in casting position, an adjustable stop member for arresting the transporter at corresponding levels before the mold, and a safety dog or interponent carried by the transporter and operable by the matrices to prevent the casting operation when the matrices are composed at said high level at the same time that the stop member is adjusted to arrest the transporter at the corresponding high level.
65. A combination as in claim 64, including a banking block carried by the adjustable stop member and movable into and out of the path of the said safety dog when the latter is held out of the transporter by matrices supported at the upper level therein.
66. In a slug casting machine adapted to be equipped with matrices formed in their casting edges with two superposed intaglio characters, the combination of a vertically movable transporter wherein said matrices may be supported at an upper or lower level according to the character selected, a slotted mold, adjustable means for positioning the transporter at a lower or upper operative level in relation to the mold, and safety means for arresting the transporter at an inoperative or non-casting level when said adjustable means are set to position the transporter at its upper level at a time when matrices are supported at the upper level in the transporter.
67. In a slug casting machine adapted to be equipped with matrices formed in their casting edges with two superposed intaglio characters, the combination of a vertically movable transporter wherein said matrices may be supported at an upper or lower level according to the character selected, a slotted mold, adjustable means for positioning the transporter at a lower or upper operative level in relation to the mold, and safety means for preventing the casting operation when said adjustable means are set to position the transporter at its upper level at a time when matrices are supported at the upper level in the transporter.
68. A combination as in claim 66, characterized by the fact that the safety means therein referred to consists of a stop member carried by the transporter and arranged to be moved to active position when matrices are supported at the upper level in the transporter, and a banking block mounted independently of the transporter and arranged to be positioned in or out of the path of the stop member according to the setting of the adjustable transporter positioning means.
69. In a slug casting machine, the combination of a vise frame hingedly mounted at its lower end so that it may be swung to open or closed positions, a vertically movable transporter slidably mounted in said frame, a rotary power operated cam, an intermediate lever controlled by the cam for operating the transporter, and a fixed stop for locating the transporter in its upper position, said stop being arranged to engage the said lever so as to permit opening and closing of the vise frame when the transporter occupies its raised position.
70. In a slug casting machine, the combination of a vise frame, a pair of upright clamping jaws mounted in said frame, a mold, a transporter for presenting a composed line of matrices between the jaws in casting relation to said mold, a ledge carried by the transporter for supporting the matrices therein, and means for advancing the mold into casting position against the matrix line, the transporter being supported against the thrust of the mold by the vise frame and the jaws being supported against said thrust by the matrix supporting ledge in the transporter.
71. A combination as in claim 70, wherein the matrices are formed with character containing recesses in their casting edges, and the rear faces of the line clamping jaws are alined with the bottoms of said recesses, characterized by the fact that the matrix line includes a pair of blank or dummy matrices formed without such recesses in their casting edges and arranged at the opposite ends of the line adjacent the jaws, for the purpose described.
72. In a slug casting machine adapted to be equipped with ordinary matrices formed with projecting ears and having character containing recesses of a given depth in their casting edges or with special matrices formed without projecting ears and having character containing recesses of greater depth, the combination of a transporter adapted to support matrices of either form and in such position that the bottoms of the deeper recesses of the special matrices will stand in the same vertical plane as that occupied by the casting edges of the regular matrices, a mold of normal height to cooperate with the regular matrices when in use, and a mold of less than normal height to cooperate with the special matrices when in use.
73. In a slug casting machine, the combination of a mold wherein the slugs are cast, means for shifting the mold from the casting position to a vertical ejecting position, means for ejecting the cast slugs from the mold, and a vertically disposed chute arranged in juxtaposition to the mold and wherein the slugs drop vertically endwise as they are ejected, said chute being arranged at a distance less than the height of a slug from the mold.
74. A combination as in claim 73, including guide means to receive the slugs as they are ejected from the mold and direct them vertically into the upper or receiving end of the chute.
75. In a slug casting machine, the combination of a mold wherein the slugs are cast, means for shifting the mold from the casting position to a vertical ejecting position, means for ejecting the cast slugs from the mold, a pair of vertically disposed trimming knives to receive the slugs as they are ejected from the mold, and a vertically disposed chute having its receiving end located directly below the knives for conducting the slugs

to the front of the machine, the space between the bottom edges of the knives being open to permit the slugs to drop from between the knives into the chute below.

5 76. In a slug casting machine, the combination of a mold wherein the slugs are cast, means for shifting the mold from the casting position to a vertical ejecting position, means for ejecting the cast slugs from the mold, a pair of vertically disposed trimming knives to receive the slugs as they are ejected from the mold, a vertically disposed chute having its receiving end located directly below the knives for conducting the slugs to the front of the machine, the space between the bottom edges of the knives being open to permit the slugs to drop from between the knives into the chute below, and a resilient plate arranged in front of the knives and adapted to prevent forward edgewise displacement of the slugs as they drop into said chute. 80

10 77. In a slug casting machine, the combination of means for casting slugs with or without overhanging type-carrying portions, means for ejecting the cast slugs, and a guide chute having at least one side wall of less than the height of a slug for conducting slugs of either form, as they are ejected, to the front of the machine. 90

15 78. In a slug casting machine, the combination of means for casting slugs with or without overhanging type-carrying portions, means for ejecting the cast slugs in a vertical position, and a vertically disposed chute arranged to receive the slugs as they are ejected, the side walls of said chute being arranged to guide the ejected slugs by their side faces irrespective of their form, and being of a height to underlie the overhanging portions of slugs of that form. 100

20 79. In a slug casting machine, the combination with a mold and means for ejecting the slugs from the mold, of a chute for conducting the ejected slugs downwardly and discharging them at one level, a fixed galley arranged at a higher level, and means for raising the individual slugs from the discharge level to the galley level. 105

25 80. In a slug casting machine, the combination with a mold and means for ejecting the slugs from the mold, of a chute for conducting the ejected slugs downwardly and discharging them at one level, a fixed galley arranged at a higher level, an elevator to receive the slugs as they are discharged from the chute and raise them to the galley level, and means for shifting the slugs from the elevator 110

30 into the galley at the latter level. 115

35 81. In a slug casting machine, the combination with a mold and means for ejecting the slugs from the mold, of a chute for conducting the ejected slugs downwardly and discharging them at one level, a fixed galley arranged at a higher level, and automatic means to receive the slugs as they are discharged from the chute and deliver them 120

40 into said galley. 125

45 82. In a slug casting machine, the combination with a mold, a vertically movable transporter for presenting composed lines of matrices in casting relation to the mold, and means for ejecting the slugs from the mold, of a galley supported 130

50 independently of the transporter, means for delivering the ejected slugs to the galley, and means operated by the transporter for stacking the slugs in the galley. 135

55 83. In a slug casting machine, the combination with a mold, a vertically movable transporter for presenting composed lines of matrices in casting relation to the mold, and means for ejecting the slugs from the mold, of a chute for discharging the ejected slugs at one level, a fixed galley arranged at a higher level, means for raising the slugs as they are discharged from the chute into a position alongside the galley, and automatic means controlled by the transporter for shifting the slugs from the elevator into the galley. 90

60 84. In a slug casting machine, the combination of a mold, a vertically movable line transporter movable back and forth between an upper line transfer level and a lower casting level in front of the mold, means for ejecting the slugs from the mold, means for arresting the transporter in its upward movement at an intermediate level, and means for holding the transporter momentarily at said intermediate level to permit the ejection of the slugs, for the purpose described. 95

65 85. A combination as in claim 84, including a fixed galley arranged at the front of the machine, a chute for discharging the ejected slugs at a point below the galley, and an elevator for lifting the individual slugs as they are discharged from the chute to the level of the galley, and characterized by the fact that the elevator is carried by the said line transporter and is adapted when the transporter is momentarily arrested at the intermediate level to register with the discharge 100

70 end of the chute and later when the transporter is at its upper transfer level to register with said galley. 105

75 86. A combination as in claim 84, including an automatic device for stopping the operation of the machine, and means carried by the transporter for rendering said device inoperative when the transporter is arrested momentarily at the intermediate level. 110

80 87. In a slug casting machine, a line transporter movable vertically back and forth between an upper line transfer level and a lower casting level at each cycle of operation of the machine, a table arranged at the upper level of the transporter, and manually operable means located directly below the table for starting the operation of the machine. 120

85 88. A series of matrices having intaglio characters of different heights and formed according to claim 33, characterized by the fact that the characters of all the matrices are located thereon with reference to a common datum line passing through the bases of the characters, and that said datum line is situated at the same distance from the alining surfaces throughout the series. 130

90 89. A combination according to claim 41, characterized by the fact that the transporter is adapted to be equipped with an auxiliary member to adapt it for the support of the matrices formed with projecting ears on their side edges. 135

95 ANTHONY J. STOUGES. 140
